UNITED STATES PATENT OFFICE.

CUMMINGS CHERRY, SR., OF CHICAGO, ILLINOIS.

APPARATUS FOR ROASTING AND PREPARING ORES FOR SMELTING.

SPECIFICATION forming part of Letters Patent No. 290,214, dated December 18, 1883.

Application filed July 10, 1883. (No model.)

To all whom it may concern:

Be it known that I, CUMMINGS CHERRY, Sr., a citizen of the United States, residing at Chicago, in the county of Cook and State of Illinois, have invented new and useful Improvements in Apparatus for Roasting and Preparing Ores for Smelting, of which the following is a specification.

The object of my invention is to provide an improved apparatus for freeing ores of their impurities—*i. e.*, all substances in combination with the metal of the ores—and preparing the ores for smelting; and the novelty consists in the construction and arrangement of parts, as will be more fully hereinafter set forth, and specifically pointed out in the claims.

My invention is designed to overcome difficulties heretofore existing in the preliminary preparation of the ores by providing suitable apparatus and means for controlling the heat applied to the ores, so as to cause all the ores treated to give a uniform product; and it consists in an apparatus having retorts or ovens adapted to be closed and made air-tight at will, within which the ores are subjected to the action of heat and vapors, and certain other details of construction, all as more particularly hereinafter described.

In the accompanying drawings, Figure 1 represents a longitudinal vertical section of an apparatus embodying my invention. Fig. 2 represents a transverse section through the line 2 2 of Fig. 1. Fig. 3 represents a horizontal section through the line 3 3 of Fig. 1. Fig. 4 is a detail of the pipes Q and R. Fig. 5 is a transverse section through the line 5 5 of Fig. 3.

My apparatus is composed, mainly, of two structures of masonry, one inclosed within the other. The external structure comprises the walls A A and dome B, and the internal, or inclosed structure comprises the walls A' A' and dome B' and a horizontal transverse portion, K. The walls A and A' thus form the two vertical chambers C C, while the horizontal masonry K forms the chamber M within the walls A' A', and beneath it the chamber L, the purposes of which several chambers will be presently described. The chamber L connects upon either side with its appropriate chamber C by means of flues V, governed by dampers o, and with the cham-

ber M by means of the flues W, controlled by the dampers p, while the said chamber M, by means of flue X and damper q, connects with the chimney D, with which chimney also connect the chambers C by means of flues controlled by the dampers r. A horizontal partition formed of a plate, a, having a central circular opening and a series of grate-bars, b, upon either side thereof, separates each chamber C from a space below, which space, by means of vertical partitions c, is formed into three parts, the center one, E, being under the central opening in the plate a, and the others, comprising the ash-pits E' E', beneath the grates b. The central opening in the plate a is occupied by a grate or valve-plate, G, having openings e' e', and adapted to slide in ways formed in the plate a, and it is manipulated by means of a rod, d, which extends through the wall of the outer structure, and is provided with a convenient handle upon the outside.

The chamber L constitutes the fire-box of a furnace; O, a grate, and P an ash-pit, the fuel being fed through the door h; and the ash-pit has a convenient door, i. The products of combustion from this chamber L may be directed to the chamber M through the flues W by opening the dampers p, the handles of which pass to the outside of the structure A, as seen in Fig. 3; or they may be deflected to either or both of the chambers C by closing said dampers p and properly manipulating the dampers o, the handles of which also extend through the walls A, as seen in Fig. 2.

Located within each chamber C is a vertical retort, F, having a hopper-mouth, F', covered by an air-tight cover, H. The lower end of this retort embraces the central opening in the plate a, and it is adapted to contain the ore which is to be subjected to heat, and within each retort is located a vertical conical tube, I, having side perforations, f'. These tubes I are designed to distribute steam and air through the ores being treated, and are closed at their upper ends, being supported approximately concentric with the retort by means of spiders g g'. The perforations f' in the pipes I preferably incline downward, to prevent the gravitating ores from clogging the same.

N designates a pipe which is adapted to

convey heated air from an outer furnace (not shown) to the fire-box L, and S a steam-pipe connection from a generator. (Not shown.) This pipe is provided with a damper, *t*, and connects with a pipe, R, which occupies a horizontal position in the chamber M, as shown in Fig. 2. Coils Q connect with the pipe R, and partitions *j* in the pipe R force the steam to pass through each of said coils, which, 5 extending upward within the chamber M, serve as superheaters. There are two sets of pipes R and coils Q shown in Fig. 1, and from each a pipe, T, connects directly with the chamber E, and thence to the retorts. Dampers *k* in the pipes R and *m* in the pipes T allow the ready 10 adjustment of the flow of steam at will. Air-pipes U, having valves *n*, also connect with the chambers E, and may, if desired, lead directly to the grate or valve G.

20 A pipe, Y, having a safety-valve, *s*, is connected with each retort F, as shown, and an inclined grate, J, in the chamber E leads the coarser ore from the retort to the door *u*.

The operation is as follows: The ores to be 25 treated are broken up or crushed in particles of suitable size and dropped or dumped into the retorts in the ovens C through the funnel-shaped tops F' F'. The cover H is then closed and the escape-valves *s s* opened. All the 30 dampers and doors of the apparatus are then closed except the dampers *o o*. The heated air from the pipe N will then enter the chamber L and pass through the passage-ways V V into the chambers C C, thus heating the ovens 35 F F and their inclosed ores. If the heat from the pipe N is insufficient to heat the ores to a bright cherry-red, or 800° to 1000° Fahrenheit, a fire is built in the chamber L upon the grate, and the heat from this fire will also 40 pass through the passage-ways V V into the chambers C C, thus increasing the heat of the air in said chambers. If the hot air from the pipe N and from the fire in the chamber L is still insufficient, or if it is desired to attain 45 the above degree of heat in a short time, a fire may be made upon the grates *bb* in the bottoms of the chambers C C, access to said grates being had by means of doors *t*. By any or all of these means the ores are subjected to heat 50 for about four hours, which will be sufficient time for the water of crystallization and constitution, oxygen, and all fugitive gases to be separated from the ores and c. boiled in an evaporated state through the escape-pipe Y.

55 The ores are now in a porous and spongy condition, their acid combinations, oxides, and refractory condition have been broken up, and their cohesive property is destroyed. If the ores are in a refractory condition, with silex 60 and other impurities, a mixture of chloride of lime or calcium and chloride of soda and pulverized carbon is mixed with the ores before they are placed in the retorts. The valves *s s* are then closed and regulated so that about 65 thirty pounds pressure of steam will open them, so as to allow a safety-escape for the steam. The retorts and their inclosed ores continue

to be subjected to the same amount of heat as before. Steam is admitted through the pipes S R and R, the dampers *l k k* being open, 70 through the coils Q Q, through the pipes T T into the chamber E, and then up into the retorts F F, and also up through the pipes I I, and through the perforations *f f'*. Steam is thus continued to be forced into the ores until the pressure is sufficient to open the valves *s s*. During this time new chemical combinations will be formed, the hydrogen from the steam will combine with the sulphur and phosphorus in the ores, and, when the above pressure is attained and the valves *s s* opened, will pass through the pipes Y Y in the form of sulphureted and phosphureted hydrogen, together with any other vapors which have been formed. This condition may easily be 85 ascertained by the odor of the gases, which may be allowed to have an escape through a small outlet-valve in the pipes Y Y. When no further odor of the above gases is discernible, this step of the process is complete. The 90 oxygen in the steam has in the meantime combined with the metal in the ores, forming oxides and peroxides, the ores being then partially oxidized.

In case it is desired to use superheated 95 steam instead of wet steam, the valves *o o* are closed, so as to cut off the hot air from the chamber L to the chambers C C, and the valves *p p* are opened, so as to admit all the hot air from the chamber L into the chamber M. The 100 wet steam which has been admitted into the coils Q Q and pipes R R will then be superheated. The dampers *m m* in the meantime should be closed, so as to keep the steam in the pipes while it is being superheated. 105 After the steam has been superheated to the degree required, the valves *m m* are opened, and the superheated steam then enters the ores in the manner above stated. When required, the valve *q* may be opened to allow the smoke 110 and gases in the chamber M to pass out of the chimney D. The valves *n n* in the pipes U U are then opened, and hot or superheated air is forced through said pipes into the ores in the retorts until the ores have become thoroughly oxidized, and they are then ready to be discharged from the retorts and out of the doors *u u*. After the process has been completed, cold air may be admitted through the pipes U U, to cool the oxidized ores previous 115 to their discharge from the retorts.

I have shown in my apparatus only two retorts; but it is evident that any number may be connected together in the same apparatus, having common central chambers, L and M, 125 and a common pipe, N.

If it is desired to use only one hot-air chamber C and one retort F, all communication between the other chambers and retorts can be cut off by the dampers leading to the same.

The pipes Y Y may terminate in condensing apparatus, where the gases and vapors from the retorts can be condensed, so that they may be afterward used for some useful purpose.

Having thus described my invention, what I claim is—

1. The combination of the vertical air-tight retorts with their escape-pipes, the closed hot-air chamber surrounding said retorts, the combustion-chamber provided with a fire-grate and connected with said hot-air chamber by flues, the hot-air pipe adapted to connect the combustion-chamber with an outside furnace, and the gas-chamber below the retort, substantially as described.
2. The combination of the air-tight retorts or ovens with their escape-pipes, the closed hot-air chambers surrounding said retorts, the grate *b* upon the bottom of said chamber, the chamber *L*, pipe *N*, and means for injecting steam into the retorts, substantially as described.
3. The combination of the closed hot-air chambers, their inclosed air-tight retorts, the perforated pipes inclosed within said retorts, and the escape-pipes *Y Y*, with the perforated valve-plate *G* and means for injecting steam and air into said retorts, substantially as described.
4. The combination of the closed hot-air chambers, their inclosed air-tight retorts having escape-pipes, the perforated pipes *I*, inclosed within said retorts, and the pipes *T*, for admitting steam into said retorts and perforated pipes, substantially as described.
5. The combination of the closed hot-air chambers, their inclosed air-tight retorts having escape-pipes, the perforated pipes *I*, inclosed within said retorts, pipes *T*, for admitting steam into said retorts and perforated pipes *I*, and the steam-superheating pipes *R*, having partitions *J*, connected with said pipes *T*, and inclosed within the superheating-chamber *M*, substantially as described.
6. The combination of the closed hot-air chambers, their inclosed air-tight retorts having escape-pipes, the perforated pipes *I*, inclosed within said retorts, pipes *T*, for admitting steam into said retorts and perforated pipes, superheating-chamber *M*, the steam-

pipes therein, flues *W*, and heating-chamber *L*, substantially as described.

7. The combination of the closed hot-air chambers, their inclosed air-tight retorts having escape-pipes, the perforated pipes *I*, inclosed within said retorts, and the air-pipe *U*, substantially as described.

8. The combination of the closed hot-air chambers, their inclosed air-tight retorts, the air-tight chambers *E*, the valve-plate *G*, slanting grate-bars *J*, and outlet-doors *u* and *v*, substantially as described.

9. The combination of the closed hot-air chambers, their inclosed air-tight retorts, the air-tight chambers *E*, and sliding grates *G*, and the pipes *T* and *U*, substantially as described.

10. The combination, with the chambers *C*, having perforated plate *a* and grates *b*, of the partitions *c*, forming the chambers *E* and *E'*, the retorts *F*, embracing the perforated plate *a*, the valve-plate *G*, and the perforated plate *I f'*, substantially as described.

11. In combination with the steam-connection *S*, pipes *R*, having partitions *J*, and the coils *Q*, as shown, the pipes *T*, retort *F*, plate *a*, valve-plate *G*, and perforated pipe *I*, substantially as described.

12. In combination with the external structure, *A B*, and internal structure, *A' B'*, forming the chambers *C*, the masonry *K*, forming the chambers *L* and *M*, the flues *V*, *W*, and *X*, the dampers *o*, *p*, and *q*, and the grates *b*, substantially as described.

13. The retort *C*, having the covered extensions *F'* and *H*, and sliding grate or bottom *G*, in combination with the hot-air chamber surrounding the retort, substantially as described.

In testimony whereof I have hereunto set my hand in the presence of two subscribing witnesses.
